US00D977600S

(12) **United States Design Patent** (10) **Patent No.:** **US D977,600 S**
(45) **Date of Patent:** **** Feb. 7, 2023**

(54) **KETTLE BELL**

(71) Applicant: **Hangzhou TuTu Technology Co., Ltd,**
Hangzhou (CN)

(72) Inventor: **Zhulin Huang**, Yunxiao (CN)

(**) Term: **15 Years**

(21) Appl. No.: **29/836,104**

(22) Filed: **Apr. 25, 2022**

(30) **Foreign Application Priority Data**

Nov. 22, 2021 (CN) 202130767607.3

(51) **LOC (14) Cl.** **21-02**

(52) **U.S. Cl.**
USPC **D21/680**

(58) **Field of Classification Search**

USPC D21/680, 681, 682, 692, 694, 677, 662
